UNITED STATES PATENT OFFICE

96,285

DESIGN FOR A BITTERS' BOTTLE OR SIMILAR ARTICLE

Gaetano Viviano, Detroit, Mich.

Application May 14, 1935, Serial No. 56,826

Term of patent 14 years

To all whom it may concern:

Be it known that I, Gaetano Viviano, a citizen of the United States, residing at Detroit, in the county of Wayne and State of Michigan, have invented a new, original, and ornamental Design for a Bitters' Bottle or Similar Article, of which the following is a specification, reference being had to the accompanying drawing, forming a part hereof.

I claim:

The ornamental design for a bitters' bottle or similar article, as shown.

GAETANO VIVIANO.
